(57) **CLAIM**

The ornamental design for a cockpit crew seating, as shown and described.

DESCRIPTION

FIG. 1 is a perspective view showing our new design of a cockpit crew seating;

FIG. 2 is another perspective view of the cockpit crew seating of FIG. 1;

FIG. 3 is a rear perspective view of the cockpit crew seating of FIG. 1;

FIG. 4 is a front view of the cockpit crew seating of FIG. 1; FIG. 5 is a rear view of the cockpit crew seating of FIG. 1; FIG. 6 is a side view of the cockpit crew seating of FIG. 1; FIG. 7 is a side view opposite that of FIG. 6 showing the cockpit crew seating of FIG. 1;

FIG. 8 is a top view of the cockpit crew seating of FIG. 1; and,

FIG. 9 is a bottom view of the cockpit crew seating of FIG. 1.

In FIG. 9, broken lines indicate environmental structure that forms no part of the claimed design.
